UNITED STATES PATENT OFFICE.

JOHN E. ULM, OF BARBERTON, OHIO.

SEWER-BLOCK.

1,338,885.

Specification of Letters Patent.

Patented May 4, 1920.

Application filed November 24, 1917. Serial No. 203,815.

To all whom it may concern:

Be it known that I, JOHN E. ULM, a citizen of the United States, residing at Barberton, in the county of Summit and State of Ohio, have invented a new and useful Sewer-Block, of which the following is a specification.

The subject of this invention is a tile intended for use in constructing sewers, arches, 10 silos and other structures.

The main object of the invention is to provide an interlocking tile.

Another object is to provide overlapping blocks.

15 A still further object is to provide a simple, durable and efficient tile.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 25 within the scope of what is claimed, without departing from the spirit of the invention.

A practical embodiment of the invention is shown in the accompanying drawings, 30 wherein:

Figure 1 is a cross section of a fragment of a cylindrical structure constructed of the tile which is the subject of this invention;

Fig. 2 is a longitudinal section taken on 35 the line 2—2 of Fig. 1;

Fig. 3 is a perspective view of the outer tile section;

Fig. 4 is a perspective view of the inner tile section.

40 Referring to the drawings by numerals of reference:

The invention consists of the co-operating, interlocking outer and inner tile blocks 1 and 2 respectively.

45 The outer tile block 1 is composed of an outer curved wall 3 and an inner concentric wall 4. These walls are joined along their longitudinal edges by a transversely concave side 5 and an opposed, transversely 50 convex side 6.

A longitudinally disposed partition wall 7, curved to correspond with the curve of the inner and outer walls 4 and 3, respectively, is positioned within each block 1 and is

joined to the outer wall 3 by a radially disposed partition wall 8.

The inner wall 4 is divided longitudinally and the edges defining the division are joined to the partition wall 7 by the outwardly converging walls 9. Each wall 9 is formed with a longitudinal dovetail groove 10.

The face of the inner wall 4 is formed with a series of ribs, preferably as here shown in the form of dovetail tongues 11.

The inner block or tile 2 consists of an inner, curved, longitudinal wall 12, concentric with an outer wall 13, which is provided with longitudinally extending dovetail tongues 14. The walls 12 and 13 are 70 connected by the division wall 15 which extends longitudinally of the block and serves to strengthen the same.

From each longitudinal edge of the block 2 rises a hollow rib indicated generally at 75 16. The outer side face of each rib is integral with the side wall of the block 2 and one face or side 17 is concave while the opposed side 18 is convex. The inner face of each rib 16 is formed with a dovetail 80 groove 19, and is inclined to correspond to the inclination of the walls 9.

One end of each block 1 is convex, as indicated at 20, to provide a transverse tongue which is adapted to enter the groove 21 85 formed by the concave edge of the opposed end of an adjacent block.

A similar formation may be had on the inner blocks 2 on which one end is convex, as at 22, while the opposite end is concave, as 90 indicated at 23.

In practice the tile is used as follows:

The inner blocks are placed in position with the tongues 22 entering the grooves or concavities 23. The side tongues 18 also 95 enter grooves 17 and cement 24 may be interposed between these latter tongues and grooves to bind the blocks in place.

The outer blocks 1 are placed in position on the inner blocks with the dovetail ribs 100 11 positioned between the similar ribs 14 of the inner blocks 2. The ribs 16 of the inner blocks fall within the grooves or channels defined by the walls 9 of the outer blocks. Cement is placed between these 105 blocks and, because of the ribs 11 and 14 and the grooves 10 and 19 serves to bind the blocks firmly together.

The ends of these outer blocks are held by the tongues 20 entering the grooves 21, while the sides are held by the tongues 6 entering the grooves 5. Cement is placed 5 between the tongues and grooves 5 to bind the sides more firmly in place.

Having thus described the invention, what is claimed as new and sought by Letters Patent, is:

- 10 1. A device of the class described embodying outer blocks having their ends respectively convexed and concaved for engagement with the corresponding elements of a like block, and comprising concentric outer, intermediate and inner walls, the intermediate wall extending entirely across the block, the inner wall comprising spaced parts joined to the intermediate wall by outwardly extending members to define a recess 15 in the outer block, the outer and intermediate walls being connected by a partition disposed approximately midway between the sides of the recess; and inner blocks extending across the joints afforded by the convexed and concaved ends of the outer blocks, each inner block including concentric inner and outer walls joined by a partition disposed approximately opposite to said joint, the inner blocks being provided at their 20 ends with hollow outwardly-extending projections, the projections on adjoining blocks being received in pairs in the recesses of the outer blocks, the ends of the inner blocks, including the extensions, being respectively 25
- 30

convexed and concaved for coöperation with 35 the corresponding elements of a like block.

2. A device of the class described embodying outer blocks having their ends respectively convexed and concaved for engagement with the corresponding elements 40 of a like block, and comprising concentric outer, intermediate and inner walls, the intermediate wall extending entirely across the block, the inner wall comprising spaced parts joined to the intermediate wall by 45 outwardly extending members to define a recess in the outer block, the outer and intermediate walls being connected by a partition disposed approximately midway between the sides of the recess; and inner 50 blocks extending across the joints afforded by the convexed and concaved ends of the outer blocks, each inner block including concentric inner and outer walls joined by a partition disposed approximately opposite 55 to said joint, the inner blocks being provided at their ends with hollow outwardly-extending projections, the projections on adjoining blocks being received in pairs in the recesses of the outer blocks. 60

In testimony that I claim the foregoing as my own, I have hereto affixed my signature in the presence of two witnesses.

JOHN E. ULM.
